US00D591679S

(12) **United States Design Patent**
Zenk

(10) **Patent No.:** **US D591,679 S**
(45) **Date of Patent:** **** May 5, 2009**

(54) **CABLE END CONNECTION**

(75) Inventor: **Petra Zenk**, Landsberg (DE)

(73) Assignee: **Pfeifer Holding GmbH & Co. KG**,
Memmingen (DE)

(**) Term: **14 Years**

(21) Appl. No.: **29/323,394**

(22) Filed: **Aug. 25, 2008**

Related U.S. Application Data

(62) Division of application No. 29/271,931, filed on Jan. 30, 2007, now Pat. No. Des. 581,869.
